Patented Jan. 14, 1919.

UNITED STATES PATENT OFFICE.

WALTER V. REID, OF RICHMOND, INDIANA, ASSIGNOR TO PETTIS A. REID, OF RICHMOND, INDIANA.

FEED MECHANISM FOR WIRE-FENCE MACHINES.

1,291,141.

Specification of Letters Patent.

Patented Jan. 14, 1919.

Application filed August 20, 1917. Serial No. 187,094.

To all whom it may concern:

Be it known that I, WALTER V. REID, a citizen of the United States, residing at Richmond, in the county of Wayne and State of Indiana, have invented certain new and useful Improvements in Feed Mechanism for Wire-Fence Machines; and I do hereby declare the following to be a full, clear, and exact description of the invention, such as will enable others skilled in the art to which it appertains to make and use the same.

This invention relates to mechanism for feeding wire and other flexible material longitudinally, and more particularly to wire fabric weaving machines used for making wire fences, wherein the stay wire is fed longitudinally or endwise across a series of strand wires into position for the action of a series of loop-forming and twisting devices and associated mechanisms, whereby loops are formed in the stay wire and wrapped around the strand wires at predetermined distances apart as the strand wires are drawn intermittently through the machine.

The object of my invention is to provide a novel and efficient feed mechanism of the character referred to with means for shifting the feed-wire alternately into and out of operative relation to the feed rolls in such manner that the wire from which the stays are to be formed, or other flexible material, may be fed to the wire working machine automatically from the coil of wire longitudinally or endwise for feeding the same lengths successively or unequal lengths alternately to form alternately long and short stay lengths.

The invention will first be hereinafter more particularly described, with reference to the accompanying drawings, which are to be taken as a part of this specification, and then pointed out in the claims at the end of the description.

In said drawings, Figure 1 is a front elevation of a wire feeding mechanism embodying my invention;

Fig. 2 is a front elevation illustrating a modification of the feed rolls and cam used for shifting the stay feed wire.

Fig. 3 is a detail perspective view of a

modified form of cam used for shifting the stay feed wire guiding means, so as to adapt the mechanism to feed wire or other flexible material lengthwise alternately in long and short lengths;

Fig. 4 is a perspective view of another form of cam used for shifting the stay feed wire for feeding the wire in the same or equal lengths successively.

Fig. 5 is a perspective view of the segmental feed roll.

Referring to said drawings, in which the same reference letters are used to denote corresponding parts in different views, the letter A may denote the machine frame on which the feed mechanism is mounted. The letters B, C and D denote, respectively, a power shaft, the cam shaft and a counter-shaft journaled in said frame. When revolved at the same speed as the cam shaft of the machine to which the material is being fed, the power shaft may be an extension of said shaft and journaled or not, as may be necessary, in the frame of the feed mechanism. The counter-shaft D may be journaled in suitable bearings bolted or otherwise secured to the machine frame, as shown, parallel with the power shaft. The feed roll drive shaft E extends above the machine frame in which it is journaled and carries a bevel pinion or gear wheel *e* which engages a similar bevel pinion or gear wheel on the shaft D, which may be driven by means of a chain *b* extending from a sprocket wheel B¹ on the power shaft B to a similar sprocket wheel on the counter-shaft D, while the shaft C is driven by a drive chain *c* extending from a sprocket wheel on the power shaft B around a larger sprocket wheel C¹ on the cam shaft C. Said sprocket wheels are so proportioned and the movement so timed as to impart the desired rotary movement to the feed rolls and the desired reciprocating movement to the wire guiding means for feeding the material in equal lengths successively or alternately in different lengths, as hereinafter described.

H and H¹ denote the co-acting feed rolls between the peripheries of which the stay feed wire is placed and gripped with sufficient force to advance the wire a given length at each revolution of the rolls. The roll H

has a part of its periphery cut away so that it will rotate a distance equal to the length of the cut away portion without gripping the wire between it and the adjacent feed roll. The peripheries of the co-acting feed rolls are normally separated sufficiently for the passage therebetween of the stay feed wire, or other flexible material, that is being fed longitudinally through the machine by means of said rolls, and the shifting of the stay feed wire sidewise, so as to bring the same into or out of operative relation to the co-acting feed rolls, for the purpose of effecting the in-feed of the wire longitudinally, or allowing the same to remain stationary during the operation of the stay attaching devices, takes place while the aforesaid cut-away portion of the larger or segmental roll H is passing the smaller or single roll H¹. The feed wire may be held in the inactive position during one or more revolutions of the feed rolls; the period of time it is so held depending upon the amount of idle time wanted between successive feeds. On the shaft C is fixed a cam K on which the lower end of a reciprocating bar L, or a friction roller on the lower end of said bar, may rest, to be operated thereby. Said bar L carries at its upper end a small feed wire guide or tube M which receives and guides the stay wire longitudinally through the machine, between the periphery of the segmental roll and the co-acting feed roll. The bar L may be supported and guided in its reciprocatory movements in eyes or sockets n, n¹ on the projecting ends of brackets N and N¹, which may be bolted or otherwise secured to the machine frame, as shown. A coiled or other suitable spring O, placed on the bar L, between the bracket N and a collar o on said bar L, tends to force said bar downwardly and hold the friction device or roller on the lower end thereof in engagement with the actuating cam K. The collar o may be secured on the bar L by means of a set screw to adapt it to be adjusted for varying the pressure of the spring. The roller H¹, or equivalent rolling means, may be mounted on a stub shaft which has its bearings in a socket formed integrally with or secured to a lever P, which is pivotally mounted on the machine frame, conveniently by means of ears or lugs on the tubular part of the lever P, apertured to receive a pivot bolt or pin p engaging registering apertures in similar lugs projecting from the machine frame. The tube or socket on the lever P may be formed integrally with a depending portion or extension p¹ of the longer arm of the lever and to said longer arm is connected at its lower end one end of a coiled or other suitable spring Q, the other end of which may be adjustably secured to the machine frame by means of an eye-bolt q passing through a hole in a bracket on the machine frame and having a nut screwed thereon for adjusting the tension of the spring, which serves to hold the lever P in contact with an adjusting screw x carried by a bracket X projecting from the machine frame, as shown, whereby the working faces or peripheries of the co-acting feed rolls are prevented from coming into contact and are kept at the desired distance apart to permit the passage of the feed wire therebetween and adapt them to grip and hold the wire with sufficient pressure to feed the required length as the rolls revolve. The cam K is constructed with peripheral lobes or projections k and k² which engage successively the lower end of the movable bar L, or the friction roller thereon, and raise said bar sufficiently to bring the stay wire centrally between the peripheries of the feed rolls, that is, between the small roll H¹ and the segment H, and hold the wire, through the wire guiding means carried by the bar L, in such position until a sufficient number of revolutions of the feed rolls has been made to feed the desired length, whereupon the spring O will force the bar L downwardly so as to bring its lower end into engagement with the arc-shaped portion or cam surface k¹, of the cam K between the two diametrically opposite lobes on said cam and at the same time bring the wire guiding means M and feed wire below the plane of the feed rolls where the wire is held and remains stationary until the loop-forming and wrapping devices have attached the previously fed stay to the strand wires, and thereupon, the strand wires being drawn through the machine the length of a stay space, the bar L will be again raised by the lobe k², to bring the wire between the peripheries of the feed rolls, and the feed wire being clamped therebetween, as the rollers are caused to revolve, another stay length will be fed, and as the rotation of the cam is continued the bar L will be lowered by engagement with the arc-shaped portion k³ of the cam K, thereby bringing the wire guiding means or feed wire below the feed rolls, where it will be held for a sufficient period of time to permit the application of a previously fed stay or stay length, and thereupon the bar L will be again raised by the boss or lobe k on the cam K, so as to bring the feed wire and guiding means into operative relation to the feed rolls, and so on, so as to intermittently feed the material a stay length; the length fed depending upon the length of the contact surface of the segment with which the adjacent co-acting feed roll is engaged and the number of revolutions of the feed rolls while the feed wire is held therebetween. A gear wheel R on the shaft E in mesh with a pinion R¹ on the stub shaft which carries the feed roll

H^1 may be used for imparting simultaneous rotary movement to the two rolls when the shaft E is revolved.

For feeding alternately long and short stay lengths, or the like, the cam K^1 , Fig. 3 may be substituted for the cam K , said cam K^1 being formed with a lobe k^4 diametrically opposite the lobe k and of greater length, for feeding a greater length of the material that is being fed. Each lobe is adapted to engage the lever L and raise and hold the stay feed wire or wire guiding means in operative relation to or between the peripheries of the co-acting feed rolls for a given length of time; one lobe being of greater length than the other so as to feed alternately a comparatively long and a comparatively short length. The length consists of multiples of what the rolls would feed in one revolution. As shown in Fig. 3 the length of one lobe is of two multiples, while the other is of three multiples; the lobes being of sufficient length to hold the stay wire in the plane of the rolls for two and three revolutions, respectively, of the feed rolls. As shown in Fig. 1, the lobes are of the same length, for feeding the same length successively, and each lobe will hold the stay wire in the plane of the rolls for two revolutions. The same result may be accomplished by omitting one lobe, as illustrated in Fig. 4, which gives a greater period of time between the successive feeds.

In the form shown in Fig. 2 of the drawings, instead of the rolling means shown in Fig. 1, there is a pair of segmental feed rolls H^2 , and H^3 and a pair of co-acting smaller rolls H^4 and H^5 , each pair of rolls being slightly separated to provide what may be termed a neutral space between the rolls, for a purpose hereinafter stated. Each of the two segmental rolls has a peripheral portion thereof cut away, as shown in Fig. 5, to form unequal segments or contact surfaces of different lengths, to adapt one segment and co-acting feed roll to feed a greater length than the other segment. The peripheries of the co-acting rolls of each pair are normally separated sufficiently for the passage therebetween of the wire or other material that is being fed longitudinally through the machine by means of said rolls. The feed wire shifting means is of the same construction and adapted to operate in the same manner as described with reference to Fig. 1, though a different form of cam is employed, to adapt the feed mechanism to feed either the same lengths successively, or unequal lengths alternately, so as to form alternately long and short stay lengths. To this end the cam K^2 has a peripheral projection k the same as the cams K and K^1 , which engages the lower end of the movable bar L , or the friction roller thereon, and raises said bar sufficiently to

bring the stay wire centrally between the peripheries of the uppermost feed rolls, that is, between the roll H^4 and the segment H^2 , and hold the wire, through the wire guiding means carried by the bar L , in such position until a sufficient number of revolutions of the feed rolls has been made to feed the desired length, whereupon the spring O will force the bar L downwardly so as to bring its lower end into engagement with the arc-shaped portion or cam surface k^1 of the cam K^2 , at one side of the boss or lobe k and at the same time bring the wire guiding means M and feed wire into the plane of the neutral spaces between the adjacent pairs of feed rolls, where the wire is held until the loop-forming and wrapping devices have attached the previously fed stay to the strand wires, and thereupon, the strand wires being drawn through the machine the length of a stay space, the bar L will be further depressed by the spring O , bringing its lower end or the roller thereon into engagement with the recessed portion k^2 of the cam K^2 , which brings the wire guiding means M centrally of the two lowermost feed rolls, H^3 and H^5 , and the feed wire being clamped therebetween, as the rollers are caused to revolve, another and shorter stay length will be fed, and as the rotation of the cam is continued the bar L will be caused to engage the arc-shaped portion k^3 of the cam and thereby raise the rod L sufficiently to bring the wire guiding means M into alignment with the neutral space between the feed rolls, where it will be held for a sufficient period of time to permit the application of another previously fed stay or stay length, and thereupon the bar L will be again raised by the boss k , so as to bring the feed wire and guiding means into operative relation to the uppermost feed rolls, and so on, so as to intermittently feed the material alternately in long and short lengths; the length fed depending upon the length of the contact surface of the segment with which the adjacent co-acting feed roll is engaged and the number of revolutions of the feed rolls while the feed wire is held therebetween. As in Fig. 1, so also in Fig. 2, the shaft E carries a gear wheel R in mesh with a pinion R^1 on the stub shaft which carries the feed rolls H^4 and H^5 for imparting simultaneous rotary movement to the two pairs of rolls when the shaft E is revolved.

If desired to feed stays of uniform length, a cam of the form shown in Fig. 4 may be substituted for the cam shown in Fig. 2, which would prevent the feed wire from being lowered sufficiently to bring the stay feed wire into the plane of the lowermost feed rolls, and would give a greater period of time between successive feeds; the lobe k being adapted to raise the lever L and bring

the feed wire into operative relation to the uppermost feed rolls, for feeding a stay length, whereupon the lobe will release or disengage the lever and allow the same to drop down and move the feed wire sidewise from between the feed rolls, in which position the wire will be held until again raised and moved in between the uppermost rolls by engagement of the lobe k with the shifting lever. The same result may be accomplished by fixing a collar T on the lever L , at the proper distance from the bracket N^1 , as shown in dotted lines in Fig. 2, so that it will serve as a stop to prevent the lever L from dropping down into the recess k^2 of the cam K^2 or lower than the neutral faces of the cam.

Suitable guiding means for the material being fed can be mounted upon a bracket or fixed part of the machine frame, to guide the material to feed rolls, and guiding means to receive the material that is being fed can also be mounted upon a bracket or other fixed part of the machine frame on the opposite side of the feed rolls, if desired. When feeding a stay-feed-wire to a fence making machine, it may be and usually is desirable to pass the wire through a wire straightener, such as shown in Patent No. 1,160,089, granted Reid, Reid & Kelley, November 9, 1915, having two series of grooved rolls mounted in different planes so that the wire may be drawn between the two sets of rolls and straightened; and such wire straightener may be mounted on a shelf or bracket cast integrally with or secured to the machine frame in such manner that the straightener so mounted may serve as one guide for guiding the wire to the feed rolls. A tubular guide such as shown in said patent may also be mounted upon the fence machine and extended close up to the feed rolls to receive the wire as fed by the rolls.

It will be understood of course that the required movement may be imparted to the feed roll shafts and cam shaft by other means than sprocket wheels and chains, as for instance, by bevel or spur gearing, and that if the machine with which this feeding mechanism is to be used has shafts properly timed, the frame design of the feed mechanism can be changed to suit the positions of such shafts when extended, or the feed roll drive shaft E can be directly connected to one of the machine shafts and motion imparted to the lever L by a cam mounted on a shaft within the machine frame, so as to dispense with the chains and sprocket wheels and bevel gearing of the specific form shown.

While my improved feed mechanism is designed and adapted especially for use upon wire fence making machines, it is obviously adapted for use in feeding flexible

material to other machines, for instance, for feeding strip material to punch presses, or other machinery, in either unequal or equal lengths, and it will be understood that the invention is not restricted in its application to wire fence making machines.

As will be seen, I may feed alternately different lengths of wire by means of co-acting pairs of feed rolls or by means of a single pair of rolls, providing the lengths to be fed are multiples of what the segment roll will feed during one revolution. For instance, if one length requires one turn and the other length requires two, three or four turns, or if the first length requires two turns and the second length requires three or four turns, the working face k of the cam should be made the length necessary to hold the wire in the plane of the rolls during the required number of revolutions of the rolls for the first length, while for the second length the cam is provided with another raised portion of greater length than but like the part k , instead of the recess k^2 as provided for use with the two pairs of rolls, the longer lobe being of sufficient length to hold the wire in the plane of the rolls for the required number of turns in excess of the number required for the shorter lobe.

Various changes may be made in the details of construction and arrangement of parts without departing from the spirit and scope of my invention; hence I do not desire to be limited to the specific constructions illustrated and described.

Having thus described my invention, what I claim as new and desire to secure by Letters Patent of the United States is:

1. In a machine for feeding wire or other flexible material endwise, the combination with a pair of feed rolls between which the material is placed, of means for rotating said rolls simultaneously in opposite directions, movable wire-guiding means, and means for throwing said guiding means into and out of operative relation to said feed rolls, including interchangeable dissimilar cams whereby the infeed of the material may be effected in either unequal lengths, alternately, or in equal lengths, successively.

2. In combination, a plurality of unequal segmental feed rolls, feed rolls beside said segmental rolls, means for rotating said segmental and co-acting rolls in opposite directions, movable wire-guiding means, and means for throwing said guiding means into and out of operative relation to said feed rolls, including interchangeable dissimilar cams, whereby the material may be fed in either unequal lengths, alternately, or in equal lengths, successively.

3. In combination, pairs of co-acting feed rolls arranged in slightly separated relation

one above another to provide a neutral space between upper and lower pairs of rolls, one pair being adapted to feed a greater length of material than the other, movable wire-guiding means, means for throwing said guiding means into operative relation to the different pairs of rolls, alternately, and means whereby said guiding means may be sustained in operative relation to one pair

of rolls only to adapt the machine to feed 10 the material successively in equal lengths.

In testimony whereof I affix my signature in the presence of two witnesses.
